US00D695616S

(12) **United States Design Patent**
Li

(10) **Patent No.:** US D695,616 S
(45) **Date of Patent:** ** Dec. 17, 2013

(54) **BOTTLE**

(71) Applicant: **FI Design, Inc.**, Chino, CA (US)

(72) Inventor: **Yue Li**, Chino, CA (US)

(73) Assignee: **FI Design, Inc.**, Chino, CA (US)

(**) Term: **14 Years**

(21) Appl. No.: **29/444,021**

(22) Filed: **Jan. 25, 2013**

(30) **Foreign Application Priority Data**

Jul. 31, 2012 (HK) 1201503

(51) **LOC (9) Cl.** **09-01**

(52) **U.S. Cl.**
USPC **D9/503**

(58) **Field of Classification Search**

USPC D9/454, 500–505, 516, 537, 539, 549,
D9/557–558; 215/379, 381–382; 220/660,
220/669–673, 675
